US0D1054781S

(12) **United States Design Patent** (10) Patent No.: **US D1,054,781 S**
(45) Date of Patent: ** Dec. 24, 2024

(54) **DETACHABLE FLIP-STRAW LID**

(71) Applicant: **Hydrojug, Inc.**, Ogden, UT (US)

(72) Inventors: **Hayden Wadsworth**, Ogden, UT (US); **Ethan Powell**, Salt Lake City, UT (US); **Ryan Holmes**, West Haven, UT (US); **Chen Huawen**, Yongkang (CN); **Chen Wiexin**, Yongkang (CN); **Li Yuejian**, Yongkang (CN); **Qiu Hui**, Hangzhou (CN); **Wang Wei**, Hangzhou (CN)

(73) Assignee: **HYDROJUG, INC.**, Ogden, UT (US)

(**) Term: **15 Years**

(21) Appl. No.: **29/961,781**

(22) Filed: **Sep. 7, 2024**

(57) **CLAIM**

The ornamental design for a detachable flip-straw lid as shown and described.

DESCRIPTION

FIG. 1 is a first perspective view of the detachable flip-straw lid design;

FIG. 2 is a second perspective view thereof;

FIG. 3 is a first side view thereof;

FIG. 4 is a second side view thereof;

FIG. 5 is a third side view thereof;

FIG. 6 is a fourth side thereof;

FIG. 7 is a top view thereof;

FIG. 8 is a bottom view thereof;

FIG. 9 is a perspective view thereof in a first alternate position of use; and,

FIG. 10 is a perspective view thereof in a second alternate position of use.

The dashed lines depict portions of the detachable flip-straw lid that form no part of the claimed design.

1 Claim, 10 Drawing Sheets
